STEAM BOILER

John T. Oxford, Morganton, N. C.

Application March 3, 1950, Serial No. 147,536

4 Claims. (Cl. 122—275)

1

This invention relates to steam boilers, and more particularly to boilers of the water tube type.

An object of the invention is to provide a boiler that will produce the maximum amount of steam for the fuel consumed, and produce it quickly and rapidly. To this end, the invention contemplates the use of fire tubes in combination with the water tubes, so as to efficiently utilize all of the heat.

Another object is to devise a boiler of this character which shall be compact, and occupy a minimum amount of space per horsepower.

Still another object of the invention is to provide a boiler which can be economically and easily manufactured, and which, while assembled by welding, shall be substantially free from strain.

In order that the invention may be readily understood, reference is had to the accompanying drawings forming part of this specification, and in which:

Fig. 1 is a perspective view of a boiler of the horizontal type, embodying the invention;

Fig. 2 is an end elevation thereof on an enlarged scale, parts being broken away;

Fig. 3 is a longitudinal vertical section substantially on the line 3—3 of Fig. 2, looking in the direction of the arrows;

Fig. 4 is a fragmentary transverse section on an enlarged scale substantially on the line 4—4 of Fig. 3, looking in the direction of the arrows;

Fig. 5 is a perspective view of a vertical type of boiler embodying the invention;

Fig. 6 is a vertical section on an enlarged scale through the boiler shown in Fig. 5, parts being broken away; and

Fig. 7 is a vertical section substantially on the line 7—7 of Fig. 6, looking in the direction of the arrows.

Referring to the drawings in detail and more particularly, first, to Figs. 1—4 thereof, my improved boiler comprises a pair of spaced parallel side water legs designated in their entirety by the numerals 1 and 2.

These water legs are each formed of upper and lower trough-shaped sections or parts of similar size united by welding, with their edges in abutting relation. The leg 1 comprises the upper and lower sections 1^a and 1^b, respectively, welded together at 1^c, while the water leg 2 comprises the upper and lower sections 2^a and 2^b, respectively, welded together at 2^c.

It will be observed, particularly by reference to Fig. 4, that each of the parts such as 2^a and 2^b is channel-shaped in cross section, and when as-

2

sembled as shown forms a hollow box-like structure.

As also best shown in Fig. 4, a series of fire tubes such as 2^d extend transversely through each channel-shaped section of each water leg and have their ends beaded into the opposite side walls thereof.

Two series of substantially semicircular water tubes extend between and connect the water legs 1 and 2. The upper series comprises tubes 3 and 4, while the lower series comprises tubes 5 and 6. As clearly shown in Fig. 3, these tubes 3 and 4, and 5 and 6, are of alternately different radii, so that they present a staggered arrangement, the tubes 3 and 5 being smaller and the tubes 4 and 6 being larger. It will be observed that the assembly of these tubes and water legs, as shown in Fig. 2, defines a substantially cylindrical structure.

In manufacturing my improved boiler, the ends of the tubes 3, 4 and 5, 6 are first inserted and beaded into the respective sections 1^a, 2^a and 1^b, 2^b of the two water legs, and these sections are then assembled with their edges in abutting relation, and welded together as indicated at 1^c and 2^c.

The boiler is supported by means of front legs 7, 8 and rear legs 7', 8', which engage under the side water legs 1 and 2.

At the lower side of the boiler is a bottom water leg 9, likewise formed of two channel-shaped sections 9^a and 9^b, welded together at 9^c with their edges in abutting relation. Nipples 10 and 11 connect the bottom water leg with the mid-point of the lower series of tubes 5 and 6, one end of these nipples being welded into the respective tubes, and the other end being beaded into the upper section 9^a of the lower water leg before the sections are welded together. A feed water pipe 12 delivers into the bottom water leg 9, as clearly shown in Fig. 3.

At the top of the boiler is a steam drum 13, this also being preferably made of two trough-shaped sections 13^a and 13^b, welded together at 13^c with their edges in abutting relation, the same as the water legs.

The usual pressure gauge 14 and water gauge 15 are preferably mounted on the steam drum 13.

The lower section of this steam drum is connected with the mid-points of the upper series of tubes 3 and 4 by means of nipples 16 and 17, one end of these nipples being welded to the tubes, and the other end being beaded into the lower section of the steam drum, before the two sections are assembled.

The cylindrical tube structure above described,

and the water legs 1 and 2 are enclosed within a shell or casing of sheet metal provided with a refractory lining. The metal shell preferably consists of a pair of end members 18 and a pair of semicylindrical side members 19, the latter being attached to the steam drum and bottom water leg, as indicated at 19^a and 19^b. The refractory lining is indicated at 20.

The end wall 18 of the casing is formed with a central opening to receive the delivery nozzle 21 of a conventional or any suitable oil burner, shown in broken lines at 22 in Fig. 1. A flue 23 taps the rear end wall of the casing at a point near the center, as shown in Fig. 3, and extends thence upwardly toward and is secured to the end of the steam drum 13. Suitable dampers 23^a and 23^b are preferably provided in this flue.

Extending longitudinally through the steam drum 13 are upper and lower series of fire tubes 24. The flue 23 communicates with the open ends of the lower series of such fire tubes, while at the front of the boiler the two series of tubes are connected by a cover plate 25. The rear end of the upper series of tubes communicates with a second flue 26, which discharges into a suitable chimney or stack 27.

From the foregoing it will be seen that the flame or products of combustion from the burner nozzle 21 are directed substantially axially of the cylindrical boiler, and that these products of combustion circulate around the water tubes 3, 4, 5 and 6, as indicated by the arrows in Fig. 3, escaping through the flue 23 and passing from this flue through the fire tubes 24, and thence out through the flue 26 into the stack. Steam is delivered from the pipe 28 tapping the upper wall of the steam drum.

It will be observed that the water tubes 3, 4, 5 and 6 all lie in parallel planes which are substantially at right angles to the axis of the cylindrical boiler and at right angles to the direction of flow of the products of combustion. Hence the products of combustion envelop and impinge directly upon these tubes, thus effectively heating the same. The tubes are also heated by heat reflected on them from the refractory lining 20 of the boiler casing, which is of course wholly outside of but adjacent the tubes.

Since the products of combustion pass through the flue 23 into and through the fire tubes 24, any heat which is not absorbed by the water tubes will be effectively transferred to the water surrounding the fire tubes, and thus a minimum amount of heat is permitted to escape to the stack. It will of course be understood that the water level is maintained at a point above the fire tubes 24.

Referring now to Figs. 5, 6 and 7, I have illustrated how the invention can be embodied in a boiler of the vertical type.

In this boiler I arrange a pair of water legs vertically at opposite sides of a generally cylindrical boiler, as shown at 29, 30 in Fig. 6. Each of these water legs, as in the previous figures, comprises a pair of trough-shaped sections welded together with their edges in abutting relation. In Fig. 7, the sections of the leg 30 are designated 30^a and 30^b, welded together at 30^c.

Extending between and connecting the water legs 29 and 30 are two series of horizontally disposed substantially semicircular water tubes 31, 32 and 33, 34. As in the previous figures, these water tubes are of alternately different radii so as to present a staggered arrangement. They all lie in planes parallel with each other and at right

angles to the axis of the vertical cylindrical boiler. The ends of these tubes are beaded into the walls of the sections of the respective water legs before assembly thereof, as in the previous figures.

The water legs 29 and 30 are formed at their lower ends with extensions 29^d and 30^d, to which are connected water inlet pipes 35 and 36, respectively.

At the upper ends of the water legs is a steam drum 37, this drum being formed of two trough-shaped sections 37^a and 37^b, welded together at 37^c with their edges in abutting relation. The upper end of each water leg opens through the bottom of the steam drum and is welded thereto, as indicated at 29^e and 30^e. Thus the water entering the lower ends of the water legs rises through the same and escapes from the upper ends thereof into the steam drum. In order to control this upward flow of water and steam, I preferably provide baffle plates 38 and 39 disposed above the open upper ends of the respective water legs and supported on posts 38^a and 39^a, respectively. Steam is delivered from the steam drum through pipe 40.

The boiler is illustrated as formed with a lower section 46 below the bottom of the water legs, and in this section may be located a suitable burner, and fluid fuel such as gas, supplied through pipe 41.

Surrounding the water tubes and water legs above described is a cylindrical casing 42 provided with a refractory lining 43, as before.

The usual pressure gauge 44 and water gauge 45 are preferably mounted on the steam drum, as shown in Fig. 5.

In order to afford access to the interior of the casing for cleaning or inspection, the casing is preferably provided with removable top sections 47, as shown in Figs. 5 and 7, one disposed at each side of the steam drum. Extending upwardly from the point where the removable sections 47 engage the steam drum is a stack throat comprising the outwardly inclined sections 48, vertical sections 49 and converging sections 50, terminating in the stack 51.

Inside of the throat structure 49, 50 and spaced therefrom is a similar structure 52, 53, constituting an inner partition. The lower edge of this inner partition is secured to the sides of the steam drum at a point just below the water level therein.

Extending diagonally through the lower section of the steam drum, and having their ends beaded into the walls thereof, are two sets of oppositely inclined fire tubes 54. These tubes are disposed in crossing relation, as indicated in Fig. 7.

The lower ends of these tubes open into the combustion space within the boiler casing below the steam drum, while the upper ends of the tubes open into the space between the inner and outer structures 50, 53 above described.

The products of combustion passing upwardly from the burner at the bottom of the boiler impinge directly at right angles against the water tubes 31, 32, 33 and 34, thus effectively heating the same, and then flow out through the fire tubes 54, and thence between the inner and outer throat structures, to the stack. Thus any heat remaining in the gases after passing the water tubes is absorbed by the water surrounding the fire tubes and a minimum amount of heat is allowed to escape to the stack.

The space within the inner partition 53 is heat-

ed by the products of combustion passing through the space between the inner and outer throat structures, and serves to subject the steam in the steam drum to a relatively low temperature superheating. The upper part of the steam drum, it will be observed, is protected from direct contact with the products of combustion.

From the foregoing it will be observed that the same general principles are employed in both the horizontal and vertical types of boiler, and that the same construction and method of assembly are employed in all water legs and also in the steam drums. It will be further seen that in both types of boiler, the water tubes are relied on to provide the main heating effect, but this is supplemented by fire tubes, for the purpose of extracting the maximum amount of heat from the products of combustion before they pass to the stack.

While I have described my improved boiler as fired by gas or oil, it will be obvious that it may be equally well fired by coal, as for example, by placing a grate in the bottom section 46 of Figs. 5 to 7, the structure being slightly modified to provide a suitable air supply, in the usual manner.

What I claim is:

1. A water tube boiler of the vertical type comprising a cylindrical casing, a pair of vertical water legs in said casing at diametrically opposite sides thereof, two series of horizontally disposed, substantially semicircular tubes extending between and connecting said water legs, a steam drum with which the upper ends of both of said water legs communicate, fire tubes extending diagonally across said steam drum entirely below the water level therein and having their ends opening through the vertical side walls thereof, one end of said fire tubes communicating with the interior of said casing, a stack, and means connecting the other end of said tubes with said stack.

2. A water tube boiler of the vertical type comprising a cylindrical casing, a pair of vertical water legs in said casing at diametrically opposite sides thereof, two series of horizontally disposed, substantially semicircular tubes extending between and connecting said water legs, a steam drum with which the upper ends of both of said water legs communicate, said drum having vertical side walls, two sets of oppositely inclined fire tubes extending diagonally across said steam drum at an angle to said side walls and having their ends opening through the same, the lower

end of each of said sets of fire tubes communicating with the interior of said casing, a stack, and means connecting the upper ends of each of said sets of fire tubes with said stack.

- 5 3. A water tube boiler of the vertical type comprising a cylindrical casing, a pair of vertical water legs in said casing at diametrically opposite sides thereof, two series of horizontally disposed, substantially semicircular tubes extending between and connecting said water legs, a steam drum with which the upper ends of both of said water legs communicate, two sets of oppositely inclined fire tubes extending diagonally across said steam drum and having their ends opening through the side walls thereof, the lower end of each of said sets of fire tubes communicating with the interior of said casing, a stack, and a stack throat structure comprising inner and outer walls, the space between said walls serving as a conduit connecting the upper ends of each of said sets of fire tubes with said stack, said inner wall enclosing the upper part of said steam drum.
- 10 4. A water-tube boiler, substantially circular in cross-section, having a pair of water legs disposed at diametrically opposite sides thereof, two series of substantially semi-circular water tubes connecting said water legs, an elongated steam drum having a horizontal bottom mounted above said tubes and water legs and communicating therewith, fire tubes extending diagonally transversely through said steam drum, and means for causing products of combustion to flow first axially through said boiler around said water tubes and in contact with the said bottom of said steam drum and then out through said fire tubes.
